DESIGN FOR A COMBINATION SALT AND PEPPER SHAKER

Helen S. Broude, Elgin, Ill.

Application October 20, 1939, Serial No. 87,780

Term of patent 14 years

To all whom it may concern:

Be it known that I, Helen S. Broude, a citizen of the United States, residing at Elgin, county of Kane, State of Illinois, have invented a new original, and ornamental Design for a Combination Salt and Pepper Shaker, of which the following is a specification, reference being had to the accompanying drawing, forming a part thereof,

Fig. 1 is a front elevational view of the combination salt and pepper shaker showing my design; Fig. 2 is a side elevational view of the same; and Fig. 3 is a top plan view of the same.

I claim:

The ornamental design for a combination salt and pepper shaker, as shown.

HELEN S. BROUDE.
